UNITED STATES PATENT OFFICE.

GEORGE W. SMITH, OF BUFFALO, NEW YORK, ASSIGNOR TO PEERLESS SAL-O-WELL CO., INC., OF BUFFALO, NEW YORK, A CORPORATION OF NEW YORK.

METHOD OF PACKING FLOOR-SWEEPING COMPOUNDS.

Application filed June 1, 1923. Serial No. 642,773.

To all whom it may concern:

Be it known that I, GEORGE W. SMITH, a citizen of the United States, residing at Buffalo, in the county of Erie and State of New York, have invented new and useful Improvements in Methods of Packing Floor-Sweeping Compounds, of which the following is a specification.

As is well known, such sweeping compounds are used in stores, schools and other places to absorb dust and prevent its flying into the air and settling upon goods, furniture, &c. Among other ingredients they contain sawdust, sand and oil, preferably par-

affine oil, which latter constitutes a large percentage of the mixture. To obtain the best results, the oil should remain thoroughly mixed with the sawdust and other ingredients.

Heretofore, such compounds have been packed for shipping and storage in one mass in suitable containers, such as sugar or salt barrels, but this has been found unsatisfactory, because the oil gradually settles to the bottom of the mass, with the result that the lowermost layer becomes excessively moist or soggy and the oil leaks from the barrel and soils the floor, while the upper layers are left dry and unserviceable, entailing considerable waste.

The object of my invention is the provision of a simple and inexpensive method of packing and storing such sweeping compounds which shall overcome these objections and maintain a practically uniform distribution of the oil throughout the contents of the package, thus keeping all portions of the mass in a useful condition and avoiding waste.

The accompanying drawing shows a form of package that may be employed in carrying out my improved method, Fig. 1 being a vertical section of the package and 2 a horizontal section thereof.

Instead of packing the sweeping compound in a single undivided mass in a barrel, or other container, the same is disposed therein in relatively shallow, superposed units, layers or divisions, each isolated from adjacent layers, whereby any settling of the oil-ingredient of the compound is confined to the depth of each layer or division, effectively preventing the oil of the entire mass from settling to the bottom of the

package and avoiding soaking of the lower layers and drying out of the upper ones.

For this purpose, the compound is freely packed in the barrel 10 or other appropriate container, in shallow separated layers, say six or seven inches in depth.

After depositing a sufficient batch of material into the barrel to form the bottom layer, the material is tamped and a removable disk or division plate 11 is placed upon it. This disk should be impervious to oil, and may consist for example, of card board treated with shellac. Another batch of the compound is then deposited upon said disk and tamped to form the second layer, and a second separating disk 11 placed upon it, and so on until the barrel is filled, when it is closed by the usual head or cover 12. As shown, the oil-impervious disks are substantially co-extensive with the transverse area of the barrel or other receptacle.

Preferably, the several disks are dished or concaved on their upper sides, as shown, this being usually done by employing disks originally flat and cut to snugly fit the barrel, and depressing their central portions below their marginal portions in the act of tamping the layers. By this dished construction of the disks, if any settlement of the oil should occur, it will gather on their depressed central portions rather than on their margins, thus rendering the oil less liable to leak over the edges of the disks onto the layers beneath.

The barrel is preferably lined with so-called glasine paper or other material impervious to oil.

As the disks engage the barrel only frictionally, they can be readily removed one after another as the compound is consumed.

By this method of packing sweeping compounds in separated shallow layers or divisions, the oil in the whole mass cannot settle to the bottom of the container, and the oil in each layer or division can settle no farther than the bottom of that particular layer. As the layers are comparatively shallow, there is not enough oil in any one of them to render the layer too wet at the bottom and too dry at the top, even if more or less settlement of the oil should take place. In any event, owing to the shallowness of each layer, the oil

if partly settled, will be re-mixed and re-distributed, by the act of removing batches or portions of the layer, either with the hand or a suitable implement.

5. Excessive moistening or undue drying of any part of the barrel-contents is thus obviated, the entire contents can be utilized without waste, and leakage of oil at the bottom of the barrel and soiling of the floor are prevented.

10. While affording these important advantages, the use of this packing method involves no material increase in the cost of the package.

I claim as my invention:

The hereindescribed method of packing and storing oil-containing sweeping-compounds in a receptacle, which consists in freely filling the receptacle with the compound and dividing the latter into relatively shallow layers by oil-impervious transverse division-plates substantially co-extensive with the transverse area of the receptacle, whereby settling of the oil in each layer is confined to the depth thereof and 20 soaking of the lower layers and drying out of the upper layers is prevented.

25. GEORGE W. SMITH.
